**POCKET TYPE CIGARETTE EXTINGUISHER
AND SAVER**

Max H. Mears, Hayward, Calif.

Application May 21, 1953, Serial No. 356,371

1 Claim. (Cl. 131—256)

The present invention relates to a pocket-type cigarette extinguisher and saver for satisfactorily and safely snuffing an ignited cigarette and carrying the same for extended use if and when desired.

Many users of cigarettes have a habit of saving so-called butts for extended or future use. They follow the practice of lighting a cigarette, taking a few puffs, and then knocking off the ignited end and placing the butt in the pocket or a special container and saving it for further use. In fact, it is sometimes necessary when one is waiting for a streetcar, bus, or the like and suddenly decides to board the same to extinguish the cigarette but preserve it for future use. Under these circumstances, there has long existed a need for a simple and economical extinguishable and safety carrying device.

It is an object of the present invention to provide just such a device, one which has a clip and is so made that it may be inserted into the coat pocket, much like a fountain pen, and thus fulfill the requirements of those who preserve butts for economical or other extended use purposes.

There are occasions when one desires to extinguish or snuff out a cigarette when he finds himself in a situation where, for example, there are no ash trays handy and where there is no place to stamp out the ignited cigarette or otherwise handily dispose of it. Therefore, it is another object of the invention to provide a device which may be used for extinguishing a cigarette which is to be handily disposed of at some convenient place of disposition.

Other objects, features and advantages will become more readily apparent from the following description and the accompanying sheet of drawings.

In the drawings:

Figure 1 is a perspective view of the improved cigarette snuffing or extinguishing device;

Figure 2 is a central longitudinal sectional view taken approximately on the plane of the line 2—2 of Figure 1, showing how the movable lever unit may be pressed to open position;

Figures 3 and 4 are sections on the lines 3—3 and 4—4, respectively, of Figure 2.

Referring now to the drawings by way of reference numerals, a primary unit is denoted by the numeral 6 and a lever unit by the numeral 8. The unit 6 is the longer of the two and it has a solid handle or finger grip 10 at one end with a suitable recessed surface 12 for convenient finger accommodation and handling purposes. The principal portion of unit 6 is channel-shaped in cross-section and therefore provides a first channel characterized by a web or bight portion 14 and spaced parallel side walls 16 and 18. The outer end of the channel is open and the end adjacent to said finger grip or handle is provided with a second channel denoted by the numeral 20. The intermediate portions of the side walls of the second channel are thickened somewhat to provide closely spaced wall portions 22—22 as perhaps best shown in Figure 1. This portion is also provided at a prescribed place with a

2

recess defining a socket which is best seen in Figure 2 and denoted by the numeral 24.

The other complementary lever-like section or unit 8 is characterized by a solid shank portion 26 which is fitted into the narrow space between the surfaces 22—22 and is there pivoted by way of the pivot pin 28. On one side of the pivot there is a wedge-shaped terminal forming a finger trip 30 which operates in the second channel 20. At this same end portion there is a socket 32 which is opposite to the socket 24 and these two sockets serve to accommodate the coil spring 34. This spring exerts tension on the finger trip 30 and serves to operate the opposite end portion of the unit 8 so that it swings into the first channel between the side walls 16 and 18. The last-named end portion is formed with a third channel which is conveniently denoted as a general feature by the numeral 36. This channel is open at its outer end, is closed at its inner end as at 35 and is opposed to the channel in the section 6 and the two channels 20 form an openable and closable receiver which is of course open at the upper end shown in Figures 1 and 2 and through which upper end the lighted end of the cigarette (not detailed) is inserted. The cigarette, incidentally, is shown in dotted lines and denoted by the reference character A in Figure 2. Here it is to be assumed that the user has smoked but a short or relatively short portion of the cigarette and desires to preserve the rest of the cigarette. He thus presses on the trip 30 against the tension of the spring and opens up the jaw-like or lever unit 8 which makes it possible to conveniently insert the cigarette into said first channel in unit 6. He then closes the section 8 and the cigarette is housed and in little or no time it will be snuffed out. It will be safe to be carried in this state. It might be mentioned here that since the device is intended to be carried about in one's pocket much like a fountain pen, the pivoted spring-pressed unit 8 is provided with a pocket clip 38. Thus, section 6 has a channel at one end portion and a handle at the opposite end portion and the other section is pivoted in the channel and has a complementary channel portion with the two channel portions cooperating and providing a satisfactory cigarette receiving and snuffing space. The channel portion of the unit or section 6 has sometimes been referred to as a sheath into which the other hinged and spring-pressed section 8 folds into compact, out-of-the-way position.

Since numerous modifications and changes will readily occur to those skilled in the art, it is not desired to limit the invention to the exact construction shown and described, and accordingly all suitable modifications and equivalents may be resorted to, falling within the scope of the appended claim.

What is claimed as new is:

55 A cigarette carrier, snuffer and saver for carrying in one's garment pocket comprising a primary unit having a handle at one end and a sheath at the opposite end, said sheath being channel-shaped in cross-section and providing a first channel which is open at the outer end and is adapted to partly receive the cigarette which is intended to be extinguished and carried about for future disposition, the portion of the handle adjacent to the inner end of said first channel being likewise provided with a second channel aligned with said first channel, and a lever unit 60 of an over-all length less than the length of said primary unit and having a pivot intermediate its ends mounted on an intermediate portion of said primary unit and having a spring pressed trip at one end normally receding and movable into the second channel and also having a portion movable into the first channel, said last named portion being likewise channel-shaped in cross-section to provide a third channel and telescopically movable com-

pletely into the first channel under normal circumstances, the first and third channels registering and providing a cigarette receiver, said last named channel-shaped portion having its outer open end spaced inwardly from the adjacent outer open end of the first channel and the trip portion thereof being spaced inwardly from the adjacent end of the handle, and said last named portion having a closure at its inner end integral therewith and formed of the same material, and said closure being spaced from said pivot and closing off the inner end of said third channel and constituting the bottom of said cigarette receiver.
